ROTARY OVEN ASSEMBLY

Carl K. Dorsey, Webster Groves, Mo.

Application July 26, 1950, Serial No. 176,040

15 Claims. (Cl. 107—59)

1

This invention relates to improvements in rotary oven assemblies, and more particularly to an improved mechanical drive assembly for rotatable shelf structures of stabilized type. It is prevalent in the trade to refer to an organization of rotary shelves for the support of products such as bakery goods, as a rotary oven, or revolving oven, although such structure does not of itself, include the oven chamber.

Certain existing equipment of the aforesaid type involves a shelf wheel, an eccentric stabilizer ring and a so-called coaster shaft or guide shaft, upon or by which the stabilizer ring is positioned or supported. Heretofore considerable difficulties and high service costs have been incurred by reason of the difficulty of maintaining dependable lubrication and hence dependably free operation of the coaster shaft. Thus such a shaft will frequently seize or freeze in its bearings, defeating its intended purpose, and resulting in an overload of drive motor and transmission. Very frequently, such shaft seizure results in scoring or grooving to the point of destruction, of the coaster shaft, or a head or wheel thereon, engaging the stabilizer ring. The present invention accordingly has as a major objective, the avoidance of such sources of destruction of parts, and the realization of a smoothly operating, stabilized-shelf oven assembly, for long periods of time and under the prevalent adverse temperature conditions encountered in oven operation. The example selected to be currently described was designed primarily for bakery ovens, but definitely without any express or implied limitation to any such specific field of application.

The present invention may perhaps best be summarized by reference to the embodiment selected for present disclosure, as including, in preferred form, a main shelf wheel shaft provided with spaced wheel elements or spiders, between and to the latter being pivoted a plurality of evenly angularly spaced shelves or trays for supporting the products undergoing baking. The individual shelves are connected through cranks or links, to a common stabilizer element, this being in the present case an annulus or ring, to which, through cranks or the like, the individual shelves are pivotally connected. The stabilizer ring is eccentrically located with respect to the axis of the shelf wheel. The stabilizer ring is guided and supported at least in part, by a stabilizer shaft, more particularly a head or separate friction drive wheel thereon operating in direct engagement with the ring. A prime mover such

2

as an electric motor is connected through a reducing transmission agency to the wheel shaft and, by preference through the latter, elements are provided for power transmission to the coaster or guide shaft for the ring in such manner that the latter is positively driven in timed relation to the shelf wheel, although the connection between the stabilizer shaft and stabilizer is preferably of some releasable type, such as a friction drive.

In furtherance of minimizing the effect of high temperatures on lubrication and on the power transmitting elements of the system, an insulated wall is provided as a part of the oven structure, and the main wheel shaft as well as the stabilizer shaft are journaled in anti-friction bearings wholly externally of the oven and externally of the insulated wall, it being preferred to provide a separate mechanical compartment at one end or side of the oven structure so as to support and house all of the principal journals for the shafts as well as the motor and all elements of the power transmission operating both the main shaft and stabilizer or coaster shaft.

25 A further important object and advantage of the present improvements is realized in the provision of a stabilizer shaft, together with means for positively rotating said shaft in definitely timed relation to the stabilizer, and hence to the main shelf wheel, thus obviating many of the heretofore prevailing destructive effects on the stabilizer ring and stabilizer shaft.

30 Yet another object of a major practical importance, is the provision of anti-friction bearings, for example those of roller type, and an advantageous location of such bearings, so as to obviate the difficulties heretofore experienced in coaster shaft maintenance and operation.

35 A still further object of the present improvements is realized in a novel physical space relation of the power transmission equipment to the oven and the thermal protection of the transmission as by an insulated barrier, from the oven proper.

40 The foregoing and numerous other objects will more clearly appear from the following detailed description of a currently preferred embodiment of the improvements, particularly when considered in connection with the accompanying drawings, in which:

45 Fig. 1 is a vertical sectional elevation showing the rotatable shelf assembly and portions of the oven structure, from which the front wall or other closure is removed to reveal the equipment internally of the oven;

Fig. 2 is a sectional view in a vertical plane, showing certain of the drive or power transmission elements, Fig. 2 being located by line 2-2 of Fig. 1;

Fig. 3 is an end elevational view of the shelf wheel or carrier, as viewed along line 3-3 of Fig. 1, and revealing the structural and functional relation of a stabilizer element to the shelf wheel;

Fig. 4 is a view similar to Fig. 3, but showing the shelves and the stabilizer ring somewhat angularly displaced, relative to the showing of Fig. 3, and

Fig. 5 is an enlarged elevational view, partly in section, of a combined shelf hanger and crank arm, together with certain parts immediately connected thereto, this figure being located by line 5-5 of Fig. 3.

Referring now by characters of reference to the drawings, the oven structure proper, which defines and encloses the baking chamber, includes a top wall 10, a bottom wall 11, a side wall 12 and an opposite side wall generally indicated at 13. Each side wall is comprised of a pair of relatively heavy vertical closure elements such as 14 which may be of metal, the pair thereof in each wall being spaced in parallel relation. Between adjacent elements 14 is a body of a mineral insulating material indicated at 15, which construction of course minimizes oven heating energy and serves materially to reduce the temperature ranges normally prevailing just outside the oven proper, and in a laterally adjacent mechanical compartment 16. This latter may be left open in part, subjected to forced air circulation if desired, and where indicated may be further enclosed by an outermost wall element 17. Heating means for the oven chamber, the latter generally indicated at 20, are omitted since, per se, constituting no part of the present improvements.

Supported within the oven chamber 20 is a main wheel shaft 21 which is of substantial diameter, and spaced axially of which are a pair of shelf wheel elements or spiders 22 at the left (Fig. 1) and 23 at the opposite end. Pivotally supported between the spiders or wheel elements 22-23 are a plurality of evenly angularly spaced shelves or trays 24. Rigidly affixed to the opposite ends of each shelf 24 are a pair of shelf hangers 25 certain of which, being those on the right hand side (Fig. 1) of the assembly constitute portions of the crank or link elements best shown in detail in Fig. 5; however, in either case the shelf hanger proper is attached to a horizontal stub shaft portion 26 as through a stud 27, the elements 26 being journaled in the periphery of the adjacent wheel or spider such as 22 or 23, an aluminum-bronze bushing 30 being located in the portion shown, in the periphery of each spider at each of the shelf hanger locations.

Fixedly attached to those of the elements 26 engaging the spider-wheel 23, is a link or crank arm 31, each of the elements 31 engaging a short journaled stub shaft portion 32 freely rotatable within an anti-friction bearing shown and preferred as a roller assembly 33. These journal assemblies are evenly disposed about the inner periphery of the stabilizer rotor or ring 34, as will appear.

The stabilizer element such as ring 34, surrounds with a wide spacing, the main drive shaft 21 which serves the shelf carrier or wheel, and is entirely free of any direct connection with the shaft and in fact may be described as floatingly

positioned in the chamber 20 although constrained to a substantially fixed position by reason of the connection thereto of the several links 31. The ring 34 is, however, guided, positioned and to some extent supported by a milled or knurled friction driving head 35, also in the chamber 20, and carried at the inner end portion of a stabilizer shaft, sometimes designated in the trade as a coaster shaft 36.

It will be understood that the assembly of shelves with the spiders or wheels 22-23, is angularly fixed to the main shaft 21. Such attachment means may include a flanged hub structure including wheel plates 37, shaft-engaging flanges 40, suitably attached to shaft 21, and studs or equivalent fastening means 41.

It may be noted that the practice of providing a shelf wheel as or in a revolving oven assembly, together with a stabilizer element, is, in a broad sense, well known in the art; however, as will have appeared, the present assembly includes numerous features of improvement which conduce to longer low-cost operational life, added stability of the shelving or trays, and a much reduced service expense.

Proceeding now to describe the mechanical drive of the shelf structure and stabilizer ring, it is a matter of convenience and compactness of assembly, as well as to provide thermal protection against heat of the oven, that the power unit and transmission elements are located in the mechanical compartment 16. These elements include a prime mover, exemplified as an electric motor 45 to which is operatively connected, as through a single or multiple V-belt 46, a speed reducer unit 47, the takeoff shaft of which carries a drive pinion 50 enmeshing with a relatively large ring gear 51 attached through a hub 52 to a continuation 53 of the main shelf wheel shaft 21. Anti-friction bearings, fully enclosed, preferably of roller type and serving the main shaft are indicated at 54 carried by wall 17, 55 carried by one of the wall elements 14, and 56 at the opposite end or side of the oven. Thus it will appear that when motor 45 is energized, pinion 50 will be driven at a considerably reduced rate, there being a further operative speed reduction between elements 50 and 51, thus driving the shelf wheel at a rate of only a few R. P. M. If desired the unit 47 may be of variable-ratio type, and if desired, motor 45 may be of variable speed type. Further and now obviously, other changes may be made in the ratio of drive, to attain any particularly desired operative speed of the shelf assembly.

It is a valuable and very important feature of the present improvements to preclude virtually any possibility of a continued operation of the stabilizer ring 34 when the shaft and drive head 35, 36 are precluded from operation, as by seizure of shaft 36. The shaft 36 is journaled, as will appear, entirely outside of the hot oven chamber 20. In the present example, shaft 36 is short, and is rotatably supported in a pair of anti-friction, preferably roller type bearings, these assemblies being indicated at 60, carried by the outermost of the adjacent paired wall elements 14, and 61 carried by the support or wall 17. All of such roller type bearings in the present assembly may be packed with a special heat-resisting lubricant, and so will operate for long periods without routine lubrication attention.

Reference will now be made to a preferred arrangement for a positively powered operation of the shaft 36 and the head or wheel 35 thereon, so

that the latter will be rotated in definitely timed relation to the shelf wheel, by which is meant the assembly of the shelves 24 and the spiders or wheels 22-23 on shaft 21. Inasmuch as the ring 34 will be given a rotative motion about its own center, concurrently with the rotative motion of the shelf wheel, the provisions to be described for rotation of element 35 will likewise produce a definitely timed driving relation between the head 35 and the ring 34. This provision consists, in the present example, of a shaft 62 journaled in roller bearing assemblies 63 and 64 and which may be identical to the assemblies 54, 55, 60 and 61. Bearing assemblies 63 and 64 are supported respectively by one of the wall elements 14, and the spaced vertical wall or support 17. Attached to shaft 62 is a gear 65 (Fig. 2) directly enmeshing with the ring gear 51, the latter being powered as above noted, by pinion 59. Also secured to shaft 62 is a sprocket 66 connected through a chain 67 to a driven sprocket 68 fixedly secured to shaft 36. A conventional roller chain is preferred for interconnecting the sprockets 66 and 68, although other forms of connection may here be used. It is desirable, however, to rotate shaft 36 in the same direction as shaft 62, hence in a direction opposite to the rotation of the ring gear 51. This relation is predicated on the assumption that the head or friction wheel 35 will directly engage the stabilizer ring 34, hence must rotate in a direction opposite to the ring 34. As will best appear from Fig. 2, this relationship is provided in the present drive, as will appear from the several arrows indicating respective directions of rotation. Thus as viewed in Fig. 2, the rotation of the ring gear 51 will be clockwise since pinion 59 operates counterclockwise. Thus the rotation of shaft 62 and therewith gear 65 and sprocket 66, is CCW, shaft 36 and head 35 also rotating CCW when similarly viewed. Thus this arrangement harmonizes with the rotation of the stabilizer ring about its center, which if viewed, as in Figs. 3 and 4, similarly to the parts in Fig. 2, would rotate clockwise in the present example.

The manner of operation of the several parts described is thought to have become fully apparent from the description of operative elements and their relationships; it may however be noted for completeness that the motor 45 acting through the reducer 47 and pinion 59, directly actuates the ring gear 51, as above noted. The line of drive from the ring gear to the shelf wheel, is directly through the main shaft 21 and the wheels or spiders 22-23. The line of drive to the coaster or stabilizer shaft, is as above referred to in a discussion of the several drive elements, through gear 65 to shaft 62 as a jack shaft serving the sprocket 66 which through chain 67 drives the stabilizer shaft 36 through sprocket 68. The drive ratio obtaining from the ring gear through to the shaft 36 is such that, in reference to the diameter of the driving head 35, the latter operatively engages the periphery of the ring 34 at a correct driving ratio such that no slippage will occur between elements 34 and 35. If however through breakage or other emergency condition, elements 35 and 36 should seize or for any other reason be held against rotation, the continued operation of ring 34 against the knurled or milled surface of head 35 will produce a high pitched warning sound, immediately apprising the operator of need for service or mechanical attention.

Thus it will have appeared that all rotative elements of the system will operate in true synchronism and in mutually timed relation and that, al-

though a releasable drive connection is preferred between shaft 36 and ring 34, there is now obviated any hazard of operational failure of shaft 36 and destruction of head 35 or shaft 36 by the stabilizer ring. It will also have appeared that the present structure serves in all respects to realize the several objectives above expressed, and numerous others implied from the more particularized description.

Although the invention has been described by making detailed reference to a selected embodiment, the detail of description should be understood solely in an instructive rather than in any limiting sense, numerous variants being possible within the full intended scope of the appended claims.

I claim as my invention:

1. In a rotary oven of a stabilized-shelf type, a rotatable shelf supporting structure, means acting responsively to rotation of said structure to stabilize the shelves, said means including a stabilizing rotor eccentrically related to said structure, a shaft arranged for locating the stabilizing rotor, and power means acting independently of the shelf supporting structure for driving said shaft.

2. In a rotary oven, a rotary shelf structure including a pair of spaced spiders, a plurality of shelves pivotally carried by and between the spiders, and a shaft on which the spiders are supported for rotatory movement; a stabilizing rotor mounted eccentrically to the spiders, and connected to the shelves for keeping same in horizontal position during rotation of the spiders, a rotatable element in driving relation to the stabilizing rotor, and power driving means operatively connected to said rotatable element independently of the rotary shelf structure.

3. In a rotary oven of a stabilized shelf type, a rotatable shelf supporting structure, a rotor acting responsively to rotation of said shelf structure to stabilize the shelves, said rotor being eccentrically related to said structure, a shaft in supporting and driving relation to the rotor, and power means acting independently of the shelf supporting structure, for actuating said shaft.

4. In a rotary oven, a wheel structure formed of a wheel shaft, spaced spiders on the wheel shaft and shelves pivotally carried by the spiders, a stabilizing rotor mounted eccentrically to the wheel structure and connected to the shelves for maintaining same in horizontal positions during rotation of the wheel structure, and a shaft powered independently of said rotor and directly operatively connected in driving relation to the rotor.

5. In a rotary oven of stabilized-shelf type, a rotatable shelf supporting structure, a rotatable stabilizer operatively connected to shelves in the shelf-supporting structure, power means connected to the shelf supporting structure for rotation of same, a shaft for positioning the stabilizer, and a power driving connection other than the shelf-supporting structure serving operatively to connect said power means to the stabilizer, and functionally independent of the rotatable shelf structure.

6. In a rotary oven comprising a wheel structure and a plurality of shelves journaled on the wheel structure and supported thereby, a stabilizing member for maintaining the shelves in horizontal position during rotation thereof, members operatively connecting the stabilizing member to the respective shelves, power means for imparting a rotary movement to the wheel structure, and a power driving connection other than the

wheel structure serving operatively to connect said power means to the stabilizing member.

7. An oven comprising a plurality of shelves, means to which the shelves are pivotally connected for moving same in an orbital path, means for preventing unwanted displacement of the shelves during the orbital movement thereof, said means comprising a stabilizer ring, a pivotal connection from such ring to each of the shelves, a rotary guide element engaging a marginal portion of the ring and power-driving means distinct from the ring, for rotating said guide element.

8. In a revolving oven structure, a shelf wheel, a plurality of shelves thereon, a shaft for the shelf wheel, a power unit, means for driving the shaft in predetermined timed relation from the power unit, a stabilizer ring connected to the shelves and acting to keep same horizontal during rotation of the shelf wheel, a shaft directly operatively connected to the stabilizer ring, and means energized from the power unit for driving the last said shaft in timed relation to the wheel and to the ring.

9. In a rotatable oven of a stabilized-shelf type, a shelf wheel, a plurality of shelves carried by the wheel, a wheel shaft, a gear on the wheel shaft, a power unit, means for driving said gear from the power unit, a stabilizer ring rotatable with the wheel and connected to and acting to keep the shelves horizontal throughout rotation of the shelf wheel, a shaft directly operatively connected to the stabilizer ring, and means for driving the last said shaft from said gear, in definitely timed relation, and in a direction of rotation opposite to that of the wheel and ring.

10. In a rotary oven of a stabilized-shelf type, a rotatable shelf supporting structure including a shaft therefor, means acting responsively to rotation of said structure to stabilize the shelves, said means including a stabilizing rotor eccentrically related to the shelf supporting structure, a coaster shaft directly operatively connected to said rotor and arranged for positioning same, and means distinct from the rotor for driving the coaster shaft in definitely timed relation to the shaft of the rotatable shelf structure.

11. In an oven, two rotary wheels or spiders rotatable about a common axis and spaced therealong, a plurality of shelves supported between said wheels, a pair of hangers for each shelf, one hanger being located at each end of each shelf, said hangers being pivotally connected to the shelf wheels and attached to the shelves, bearings at the ends of said shelves adjacent said wheels, said bearings being of sleeve type, a stabilizer ring eccentric to the axis of said shelf wheels, and bearings on said ring, the last said bearings being of roller type, and a link connection between the stabilizer ring and each of said shelves, the eccentricity of said stabilizer ring being such that said bearings and links coact to maintain the shelves horizontal in all positions of the wheels, and a rotary powered element operatively engaged by the stabilizer ring, and through which a turning moment is directly applied to said ring during operation of the wheels.

12. In a rotary oven assembly, means enclosing an oven chamber, said enclosing means including a thermally insulated vertical wall, a revolving shelf wheel in the oven chamber, a wheel shaft extending through said insulated wall, a power unit located externally of the insulated wall, and operatively connected to said wheel shaft, a shelf-stabilizing ring in the oven chamber coacting with the shelf wheel, a ring-positioning shaft located

partly in the oven chamber and partly outwardly of the insulated wall, journals for each of said shafts, said journals being located laterally and exteriorly of the insulated wall, and power transmission means located outside of the oven and insulated wall, and being actuated by the power unit and operatively connected both to the shelf wheel shaft and to the ring positioning shaft.

13. In a revolving oven assembly, a plurality of shelves, a wheel structure by which the shelves are carried, a stabilizer ring located externally of the wheel, a link element pivotally connecting the stabilizer ring and each of the individual shelves, a main supporting shaft for the shelf wheel, a ring-guiding shaft engaging the periphery of the stabilizer ring, and located to support and guide the ring, means for rotatably actuating said main wheel shaft, and power transmission means interconnecting the first and second said shafts, whereby to drive the second said shaft in predetermined timed relation to, but in a direction opposite to that of the first shaft.

14. In a revolving oven assembly, a revolving shelf assembly within the oven chamber and including a pair of spaced spiders, a main shaft by which said spiders are rotatably carried, a plurality of shelves for supporting articles to be exposed to baking temperature, said shelves being provided with hangers, one at each end of each shelf, the shelf hangers being journalled in the spiders, a plurality of cranks, one for each shelf, carried by the shelves and one of the spiders, a stabilizer ring free of the said main shaft, but surrounding same in substantially spaced relation, the stabilizer ring being located in the oven chamber, and pivotally connected to the several cranks, and therethrough to the shelves, the ring being located eccentrically of the main shaft and the spiders, a coaster shaft serving as a guide for the stabilizer ring, the coaster shaft provided with roller type bearings, a metal friction wheel carried by an inner end portion of the coaster shaft, and frictionally engaging the outer periphery of the stabilizer ring, a power unit and transmission means including a ring gear carried by said main shaft, a motor, a speed reduction unit, a pinion engaging the ring gear and driven from said reduction gear unit, a gear driven from the ring gear and a power connection from the ring-driven gear to the coaster shaft, and arranged for rotation of the coaster shaft in timed relation to, but in a direction opposite the direction of rotation of the main shaft.

15. In a revolving oven assembly, an enclosure defining an oven chamber, the enclosure structure including a thermally insulated vertical side wall, and an auxiliary closure spaced from said insulated wall to form therewith a mechanical compartment, a revolving shelf assembly within the oven chamber and including a pair of spaced spiders, a main shaft by which said spiders are rotatably carried, a plurality of shelves for supporting articles to be exposed to baking temperature, said shelves being provided with hangers, one at each end of each shelf, the shelf hangers being journalled in the spiders, a plurality of cranks, one for each shelf, carried by the shelves and one of the spiders, a stabilizer ring free of the said main shaft, but surrounding same in substantially spaced relation, the stabilizer ring being located in the oven chamber, and pivotally connected to the several cranks, and therethrough to the shelves, the ring being located eccentrically of the main shaft and the spiders, a coaster shaft serving as a guide for the stabilizer

ring, the coaster shaft bridging the insulated wall and the auxiliary closure and provided with roller type bearings located entirely outside of the oven chamber, and a pair of such bearings being carried respectively by the insulated wall and the outer closure, a metal friction wheel carried by an inner end portion of the coaster shaft within the oven chamber, and frictionally engaging the outer periphery of the stabilizer ring, a power unit and transmission means within the mechanical compartment, and including a ring gear carried by said main shaft, a motor, a speed reduction unit, a pinion engaging the ring gear and driven from said reduction gear unit, a gear driven from the ring gear and a power connection from the ring-driven gear to the coaster shaft, and arranged for rotation of the coaster

shaft in timed relation to, but in a direction opposite the direction of rotation of the main shaft, the said motor, reduction gear unit, and the recited transmission elements associated with the respective shafts, being located in said mechanical compartment.
